UNITED STATES PATENT OFFICE.

WILLIAM B. CARNAY, LOUIS SCHWARZ, AND CHARLES SCHWARZ, OF
BALLSTON SPA, NEW YORK.

FROST-GUARD FOR REFRIGERATOR-BUILDINGS.

SPECIFICATION forming part of Letters Patent No. 679,526, dated July 30, 1901.

Application filed February 28, 1901. Serial No. 49,222. (No model.)

To all whom it may concern:

Be it known that we, WILLIAM B. CARNAY, LOUIS SCHWARZ, and CHARLES SCHWARZ, citizens of the United States of America, residing 5 at Ballston Spa, in the county of Saratoga and State of New York, have invented certain new and useful Improvements in Frost-Guards for Refrigerator-Buildings, of which the following is a specification, reference being had 10 to therein to the accompanying drawings, in which—

Figure 1 represents a perspective view, Fig. 2 a sectional view, and Fig. 3 a vertical sectional view, of our improved guard or curtain. 15 A serious need has been felt in connection with refrigerator-buildings for an efficient frost-guard for guarding or screening the goods in the storage-rooms adjacent to the refrigerating-pipes on the side walls of the 20 storage-rooms, and the lack of means to fill this need frequently occasions loss of either goods or valuable storage-space; and it is the object of this invention to provide a simple device which will serve as an efficient guard 25 or screen to prevent frost collecting on the goods stored adjacent to the cooling-pipes, and thus prevent the cold penetrating the goods sufficiently to destroy or damage them, thereby permitting the utilization of the full 30 capacity of said storage-rooms, as more fully hereinafter set forth.

The preferred form of the guard is shown in the accompanying drawings, in which the outer face (the face farthest from the cooling-pipes) of the guard is constructed of a series 35 of closely-joined spruce boards *a* of a suitable thickness and secured together by a layer *b* of insulating-paper and strips of wood *c*, the paper lying directly against and covering the 40 entire inner faces of the boards and the strips being secured against the paper around the edges thereof and at suitable intervals—say eighteen inches apart. Upon the strips *c* is placed another layer *d* of insulating-paper, 45 which covers the entire inner face of the device and is fastened by another series of wooden strips *e*, nailed to the strips *c*. Suitable means, such as hooks and eyes, is provided for detachably suspending the guard 50 from the ceiling of the storage-room, preferably about ten inches from the wall holding

the cooling-pipe, and to maintain the suspended guard approximately parallel with said wall it is provided at its lower end with inward-extending braces or legs *f*, which are 55 adapted to rest against said wall, as shown.

The completed guard or curtain is coated with a solution of calcium-chlorid brine, and this coating is desirably renewed each season.

It will be observed that the wall of closely-joined board, the layer of insulating-paper, and the dead-air chamber formed between the paper layers form an effective barrier in preventing the frost penetrating the goods adjacent to the pipes, thus permitting goods that 60 would be injured by being frozen to be stored in these rooms close up to the frost-guard, thereby utilizing to its fullest extent the capacity of these rooms. The brine coating serves to prevent frost gathering upon the 65 guard and at the same time does not become tainted or emit objectionable odors.

It will be observed that the guard is additionally advantageous in that it assists in promoting circulation of cold air, the warmer 70 air entering over the top of the guard and falling through the space between the guard and the wall as its temperature is reduced by contact with the cooling-pipes. To insure 75 this circulation, it is evident that there must be a space for the entrance of the warmer air 80 between the top of the guard and the ceiling of the room, as shown.

Having thus fully described our invention, what we claim is—

1. A non-conducting frost-guard for the purpose set forth provided with means for detachably suspending it from the ceiling and at its lower end with inward-extending arms for maintaining it approximately parallel with 90 the wall holding the pipes to be guarded against.

2. In combination with a cold-storage room, the side wall of which is provided with refrigerating-pipes and whose ceiling is provided 95 with the upper members of hook-and-eye connections, of a non-conducting frost guard or curtain provided at its upper edge with the lower members of said hook-and-eye connections and at its lower end with means for 100 maintaining it approximately parallel with the wall carrying said pipes, the upper edge

of said frost guard or curtain lying at a distance below the ceiling and its lower edge terminating short of the floor.

3. A frost-guard for the purpose set forth, 5 consisting of a solid wooden outer face, a layer of insulating-paper on the inner side thereof, a series of separated strips, another layer of insulating-paper on said strips, forming a dead-air chamber, and another series of strips, 10 the whole being fastened together.

In testimony whereof we hereunto affix our signatures, in the presence of two witnesses, this 23d day of February, 1901.

WILLIAM B. CARNAY.
LOUIS SCHWARZ.
CHARLES SCHWARZ.
